INVENTOR
WILLIAM H. CARSTEN

BY
Richard L. Scott ATTORNEY

UNITED STATES PATENT OFFICE

WILLIAM H. CARSTEN, OF SEATTLE, WASHINGTON

PUMP

Application filed February 21, 1927. Serial No. 169,989.

This invention relates to improvements in pumping apparatus of that character whereby water may be raised from a well, or other deep place, by means of compressed air that is intermittently delivered into a cylinder submerged in the water so that the cylinder fills during the intervals that the air pressure is cut off.

The principal object of this invention is to improve upon the device of my co-pending application, filed March 17, 1925, Serial Number 16,123, by the elimination of several pipes which made the apparatus, as before constructed, rather cumbersome. Also, to provide an air control valve of a novel and more satisfactory character and to provide means for delivering air pressure into the water storage tank during the intervals that the air pressure is cut off from the air cylinder and while the latter is filling, so as to maintain an even pressure in the storage tank regardless of the intermittent application of air to the pump cylinder.

Other objects of the invention reside in the details of construction of the various parts and in their novel arrangement and combination, whereby a compact and very satisfactory and efficient mechanism is provided.

In accomplishing these objects, I have provided the improved details of construction, the preferred forms of which are illustrated in the accompanying drawings, wherein—

Figure 1 is a side elevation of a pumping apparatus embodied by the present invention; the pump cylinder and a part of the water storage tank being shown in vertical section for better illustration.

Figure 2 is a sectional view taken on line 2—2 in Figure 1, showing the valve actuating mechanism whereby air pressure is admitted to or cut off from the pump cylinder.

Figure 3 is a sectional view of the valve, taken longitudinally of the plug.

Figures 4 and 5 are sectional views of the valve taken, respectively, on the section-lines 4—4 and 5—5 in Figure 3.

Referring more in detail to the several views of the drawings—

1 designates an elongated pump cylinder, closed at its upper end by a cap 2 and having a bell 3 threaded into its lower end. 55 The lower end wall 4 of the bell has a central opening 5 within which a valve 6 is fitted and which operates to admit water into the cylinder 1 through the bell but which automatically closes to prevent any 60 outflow. Fastened to the lower end of the bell and covering the opening 5 is a perforated cover plate 7 which serves to prevent sand, or other foreign objects, from clogging the valve opening. 65

Threaded through the cap 2 of the cylinder is a nipple 8 and extending from this, downwardly within the cylinder to near its lower end, is a pipe 9 through which water is discharged from the cylinder, and threaded into the upper end of the nipple is a pipe 10 that leads to the upper end of an air and water-tight storage tank or reservoir 11. Adjacent the nipple 8, a back check valve 12 is interposed in the pipe 10 to prevent back flow into the cylinder during intervals when air pressure is cut off. 75

The pump cylinder 1, when in use, is suspended within a well, as designated at 13, so as to be submerged by water which will then flow into the cylinder through opening 5 at times when air pressure is cut off from the cylinder. The means provided for supplying air pressure for lifting water from the well through pipes 9 and 10, comprises an air 80 compressor 15, which may be of any suitable character and driven by any suitable power. As here shown, the compressor is driven by an electric motor 16 through the intermediary of a belt 17 that operates about a belt 85 wheel 18 fixed on the compressor shaft 19 and about a relatively small belt wheel 20 fixed to the motor shaft, 21.

Air that is compressed in the cylinder 24 of the compressor is delivered through a pipe 95 25 into a high pressure air storage tank 26 which has connection, through a pipe 27, a fitting 28, a short pipe 29 and a valve mechanism, designated in its entirety by numeral 30, with a pipe 31 that leads to the well and 100

to the pump cylinder 1 and opens into the latter through the cap 2.

The valve mechanism 30, as shown best in Figures 3, 4 and 5, comprises a housing in which a tapered plug 35 is revolvably fitted and which is held tightly to its seat by means of a spring 36 that bears against the end of the housing and against a nut 37 threaded into a coaxial stem 38 projecting from the smaller end of the plug. The valve housing is provided, at one side, with a tapped opening 39 for receiving the pipe 29 and at a point diametrically opposite the opening 39, is provided with a channel 40 that leads laterally and into an opening 41 with which the pipe 31 connects. The plug 35 is provided with a transverse port 44 which, by certain positioning of the plug as shown in Figures 3 and 5, will connect the pipes 29 and 31 so that air pressure may flow therethrough into the pump cylinder 1. The plug is also provided with a transverse passage 45, located at right angles with respect to passage 44, and this, by certain positioning of the plug, will connect the pipe 31 with an exhaust port 46 in the housing to thereby provide for the escape of air from the cylinder 1 while the latter is filling with water. The ports 44 and 45 bear such relation to each other that when one is closed the other is open, and vice versa.

At the larger end of the valve plug 35 is a projecting stem 46 and fixed to this is a lever 47, one end of which is equipped with a weight 48 which operates to yieldably hold the valve in that position, shown in Figures 3 and 5, at which there will be open connection provided between pipes 29 and 31 for the admittance of compressed air to the pump cylinder. At the other end of the lever is a cam 49 adapted to be engaged by a plate 50 fixed on the rim of a revolving gear wheel 51 so as to be moved to a position at which the valve plug will cut off admittance of air pressure to the cylinder 1 and will open the pipe 31 to atmosphere through valve ports 41 and 46.

The wheel 51 is revolvable on a pivot bolt 54 fixed in a bracket 55 that is mounted on the frame, or foundation, 56, on which the various parts of the device are located. It revolves in a vertical plane perpendicular to the axis of the valve plug and it is driven by a worm gear 57 on a shaft 58 supported in bearings 59 and 60. The worm shaft 58 has a belt wheel 61 fixed thereon in alignment with a small belt wheel 62 on the compressor shaft 19 and a belt 63 operatively connects the wheels. By this connection, the wheel 58 is made to revolve at a proper speed for timing the opening and closing of the valve for the admittance of compressed air into and its exhaustion from the pump cylinder 1.

In order to supply air pressure directly to the water storage tank 11 at times when the

cylinder 1 is filling with water, and during which time the pressure is somewhat reduced, I have extended a small pipe 70 from the top of tank 11 to the valve 30. This is tapped into a port 71 located in the side of the valve housing in the plane of the plug channel 44. There is also provided a small port 75 in the plug connecting with channel 44 and adapted to provide a connection between pipe 29 and pipe 70 when the plug is turned to a position to cut off air pressure to the pump cylinder. A valve cock 78 is provided in pipe 70 for controlling the rate or amount of flow of air to the tank 11 and a back check 79 is provided to prevent back flow. Electric circuit for the motor is delivered thereto under the control of a switch mechanism 80 and this is of that character adapted to be operated between "on" and "off" positions by a control device 81 actuated by air pressure delivered thereto through a connection 82 with pipe 70 so that the apparatus will act automatically to start when the water pressure falls below a certain amount and to stop when a certain predetermined pressure is reached.

An outlet pipe 85 leads from the lower end of the tank 11 and this may extend to a point where the water is to be used and would there be equipped with a faucet 86.

With the device so constructed, its operation would be as follows:

With the pump cylinder 1 lowered into a well sufficiently to be submerged by the water, and with the cylinder connected by the pipe 10 with the top of the storage reservoir 11 and the pipe 31 connected through the valve mechanism 30 with the air storage reservoir 26 and compressor 15, the motor 16 is started to maintain the air pressure and to drive the timing gear 51. As the compressor operates it builds up an air pressure within the tank 26 and when the valve 30 is opened this air pressure is admitted through the pipe 31 into the top of the cylinder 1 so as to force the water from the cylinder through the pipes 9 and 10 into the tank 11. The rate of rotation of the gear 51 is so timed that the plate 50 will contact with the lever 49 at about the time the cylinder 1 is emptied of water, and the valve plug will be rotated to a position at which the compressed air supply will be cut off from the channel 40 in the valve and the pipe 31 will be connected with atmosphere through the plug channel 45 and valve opening 46. This permits the air within the cylinder 1 to escape to atmosphere and the cylinder to fill with water. At about the time the cylinder is again filled the plate 50 on the timing gear 51 again contacts with the valve lever and actuates the valve to again connect pipe 31 with air supply and to shut off the opening to atmosphere so that the compressed air will be delivered to the cylinder 1 and the

water therein again forced through pipes 9 and 10 to the storage tank 11. This operation continues until sufficient water has been delivered to the storage tank 11 that the air pressure is built up sufficiently to actuate the control mechanism 81 to close the switch 80 and thereby stop the motor.

The whole system is rendered automatic by the following means: When it is desired to draw off a supply of water from the tank 11, the faucet 86 is opened. As the water lowers in the tank 11 the air pressure is reduced and this, through the connecting pipes 70 and 82 with the control mechanism 81, opens the switch 80 and starts the motor 16 which drives the compressor to build up an air pressure in the tank 26 and this pressure is intermittently delivered to the pump cylinder, through pipes 27, 29 and 31, to expel water from the cylinder after each filling operation. The motor continues to operate until sufficient water is lifted into the tank that the air pressure therein reaches a point at which the control mechanism will be actuated to stop the motor.

The rate of rotation of the timing gear may be varied in accordance with the time required for the cylinder 1 to fill with water and it may be equipped with one or more of the trip plates 50 as is required and these may be made in proper lengths required to hold the valve closed for a sufficient length of time that the cylinder may fill with water.

Having thus described my invention, what I claim as new therein and desire to secure by Letters Patent, is:

1. In a pumping system of the character described, a pump cylinder having a water inlet at its lower end, a closed water storage tank, a supply pipe leading from near the lower end of the pump cylinder into the storage tank, a back check valve in said pipe, an air pump, a conduit connecting the air pump with the top of the pump cylinder and a valve in said conduit having an exhaust port and having a conduit connection with the storage tank, means for adjusting the valve to a position at which air will be admitted into the pump cylinder to expel water therefrom into the storage tank and adjustable to another position to permit air to exhaust from the cylinder through said exhaust port of the valve as the cylinder fills with water through the inlet valve and to admit air into the storage tank from the pump during the interval the tank is filling.

2. In a pumping system of the character described, a pump cylinder having a valved inlet at its lower end, a closed water storage tank, a supply pipe connecting the pump cylinder with the storage tank and having a back check valve therein, an air pump, an air storage tank connected to the pump, a conduit leading from the air storage tank into the top of the pump cylinder, a valve

in said conduit comprising a housing having an exhaust port and a conduit connection with the water storage tank, a back check valve in the conduit and a valve plug adjustable to one position for admitting air from the air tank into the pump cylinder to expel the water from the latter and adjustable to another position to exhaust air from the pump cylinder as it fills with water and to connect the air storage tank with the water storage tank, a lever fixed to the valve plug, a weight on one end of the lever whereby the valve will normally be held at its first mentioned position, means for driving the pump, a gear wheel rotatably driven by connection with the pump driving means and a plate fixed to the gear adapted to engage the lever of the valve plug to move the plug to its second mentioned position.

Signed at Seattle, Washington, this 7th day of January, 1927.

WILLIAM H. CARSTEN.
